(57) **CLAIM**

The ornamental design for bridge portion for binoculars, as shown.

DESCRIPTION

FIG. 1 is a front perspective view of bridge portion for binoculars showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken line showing of the binoculars and focusing wheel in all views is for illustrative purposes only and forms no part of the claimed design.
